Primary Examiner — Sandra Snapp

(57) **CLAIM**

The ornamental design for a cover for a dispenser, as shown and described.

DESCRIPTION

FIG. 1 is an isometric view of a front, top, and left side of the ornamental design for a cover for a dispenser;

FIG. 2 is a front elevation view of the cover of FIG. 1;

FIG. 3 is a rear elevation view of the cover of FIG. 1;

FIG. 4 is a left side elevation view of the cover of FIG. 1, wherein the right side elevation view is a mirror image of the left side elevation view;

FIG. 5 is a top plan view of the cover of FIG. 1; and,

FIG. 6 is a bottom plan view of the cover of FIG. 1.

The broken lines in the drawings depict environmental subject matter only and form no part of the claimed design.

1 Claim, 4 Drawing Sheets
